UNITED STATES PATENT OFFICE

2,524,587

TRIPLE-PURPOSE ADAPTER FIXTURE
FOR SKATES

Miles M. Bacon, Jacksonville, Fla.

Application March 31, 1949, Serial No. 84,546

2 Claims. (Cl. 280—11.27)

1

The present invention relates to a multiple-purpose bracket or fixture which is expressly designed to be securely fastened to the under side of the toe plate of a skating rink roller skate which, more specifically, takes the form of a so-called triple-purpose adapted fixture in that it constitutes a novel hanger for the usual front shoe clamp, for a wheel and axle assembly hanger unit and serves to properly buttress the brace arm portion of the hanger unit.

Usually the bracket which is employed as a hanger and separator for the double-jawed shoe clamping unit is a simple notched lug and the hanger for the wheel and axle assembly is mounted on and associated with an independent bracket or fixture.

In carrying out the principles of the present invention, I have found that by integrating the stated lug with the hanger accommodating bracket and making a more massive single unit out of the two parts as currently used and by incorporating other features, a skate equipped with the new multiple purpose, one-piece adapter fixture is rendered more reliable, is greatly strengthened and provides a superior high-grade skate less susceptible to breakage.

More specifically, the present invention has to do with a single casting which is characterized by a heavy stress and strain distributing body or plate portion equipped with a slotted hanger lug at the forward end to suspend and retain the shoe clamping means or unit, has a rearwardly and downwardly inclined buttressing member to stabilize and strengthen the action of the coacting brace arm and, in addition, has a socketed abutment at the rearward end to accommodate a conventional type cushioned bolt which serves to anchor the wheel and axle assembly hanger unit in place.

In reducing to practice a preferred embodiment of the invention, I have evolved and produced a single casting which is economical and of the utmost in simplicity in form and design and which is characterized by a centrally disposed flanged ovate plate portion to be riveted to the under side of the toe-plate, which carries a depending lug with attaching ears on the forward end and a block-like abutment at the rearward end, said abutment being aptly shaped and located, socketed and also provided with an attaching ear.

Other objects and advantages will become more readily apparent from the following description and the accompanying illustrative drawings.

2

In the drawings:

Figure 1 is a bottom plan view of a toe-plate with my improved triple-purpose adapter fixture secured in place, with the shoe clamping unit attached and with the wheel and axle assembly and hanger unit removed.

Figure 2 is a side elevational view of the structure seen in Figure 1 with the hanger unit and wheel and axle means operatively associated and in place.

Figure 3 is a central longitudinal sectional view on the line 3—3 of Figure 1, looking in the direction of the arrows.

Figure 4 is a transverse or cross section taken on the vertical line 4—4 of Figure 2, also looking in the direction of the arrows.

Referring now to the drawings by distinguishing reference numerals and lead lines, the fragmentary portion of the toe-plate shown, which is conventional, is denoted by the numeral 6. The improved, triple-purpose adapter bracket or fixture, as a unitary device, is denoted by the numeral 1 and is best shown in Figure 1. The conventional double-jawed shoe clamp or unit is denoted by the numeral 8.

The wheel assembly and axle unit comprises the axle 9 and customary wheels 10 thereon.

The hanger unit for the wheel and axle assembly means is denoted by the numeral 11 and is substantially conventional and includes a bearing 12 rockably mounted on the axle, an outstanding cup 13 on one side and a brace arm 14 on the opposite or diametrically opposed side terminating in a reduced projection 15 (see Fig. 3). The unit also includes a headed bolt or fastening screw 16, a washer 17, a cushioning sleeve 18, a cup-washer 19 and a complementary nut 20.

The clamp unit 8 embodies the usual two-way threaded feed screw 22, tool grips 23, guides 24 which are welded or otherwise suitably fixed on the toe plate 6, as usual, and clamp straps 25 with lateral portions 26 threaded on the bolt and shoe sole grips 27. Usually this unit (feed screw 22 and clamp straps 25) is suspended in a simple relatively frail and unreliable notched lug carried by the toe-plate 6.

The improved one-piece multiple-purpose bracket or unit comprises a substantially ovate, heavy plate portion 28 with a marginal correspondingly shaped reinforcing rim or flange 29, said plate held in place by rivets 30. Within the limits of the rim or flange is a forwardly and downwardly inclined buttressing member 31 with a socket 32 to accommodate the extension 15 as shown in Figure 3. The lug 33 is segmental

shaped and has a keyhole slot 34 (see Fig. 3) and also has outstanding attaching ears 35 held in place by rivets 36. The keyhole slot obviously serves to facilitate assembling the feed screw and after the clamp means is applied, the feed screw is fitted into the restricted end portion of the slot. The abutment at the rearward end of the plate is of block-like form and is denoted by the numeral 31 and has a screw-threaded socket 38 to accommodate the assembling bolt 16, there being an attaching ear 39 riveted to the toe-plate as at 40. The brace strap, which is conventional, is denoted by the numeral 41 and has one end riveted, as at 42, and the other end apertured and laterally bent, as at 43, and interposed between the nut 20 and the adjacent inclined or slanting end of the abutment. It follows that the abutment therefore serves as suspension or supporting means for the bolt-equipped end of the hanger unit 11. The buttressing member 31 serves as a backup anvil for the brace arm 14.

By forming the adapter 7 of a single casting made up of the parts shown and described, an effective and reliable mount is thus provided to suspend and hold in place the shoe clamp unit 8, the hanger unit 9, and consequently the wheel and axle assembly unit, and provision is made to properly accommodate the end-thrust action of the brace arm 14. Added strength and rigidity is assured by the presence of the substantially endless reinforcing flange 29.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

5 1. In a rink-type roller skate of the kind shown and described, in combination, a toe-plate, a wheel and axle assembly, a hanger unit for said assembly embodying an axle bearing provided on one side with a cup carrying an attaching bolt and nut retained cushioning sleeve surrounding said bolt and seated in said cup, and further provided with a diametrically opposite end thrust brace, the latter at an approximate acute angle to said bolt, shoe clamping means embodying a two-way feed screw and sole gripping clamp straps threaded on said feed screw and shiftably mounted on said toe plate, and a one-piece triple-purpose adapter unit embodying a relatively heavy plate fixed to said toe plate adjacent to said shoe clamping means, said plate having a vertically disposed hanger lug at its forward end, said lug being of heavy duty proportions, having a vertical keyhole-slot through which said feed screw passes, and terminating in lateral outstanding ears secured to said toe-plate, said unit also including a buttressing member against which said brace is angularly propped, and a socketed abutment for said bolt at the rearward end of said plate, said abutment inclining toward said lug.

10 2. A skate attachment of the class shown and described comprising a single casting embodying an ovate attaching plate with a lateral correspondingly ovate marginal rim-flange and having a socketed abutment at its rearward end, a buttressing anvil at its forward end within the confines of said rim, and a heavy duty lug, said lug having a keyhole-slot and terminating in a pair of outstanding attaching ears.

25 MILES M. BACON.
